The ornamental design for a drifting kart, as shown and described.

DESCRIPTION

FIG. 1 is a perspective view of a drifting kart which embodies my design.

FIG. 2 is a different perspective view of the drifting kart of FIG. 1.

FIG. 3 is a top view of the drifting kart of FIG. 1.

FIG. 4 is a left side view of the drifting kart of FIG. 1.

FIG. 5 is a right side view of the drifting kart of FIG. 1.

FIG. 6 is a front view of the drifting kart of FIG. 1; and,

FIG. 7 is a rear view of the drifting kart of FIG. 1.

Dashed lines illustrate portions of the drifting kart that form no portion of the claim.
